UNITED STATES PATENT OFFICE.

ROBERT WEBER, OF DRESDEN, GERMANY.

SHUTTING OR FASTENING CONTRIVANCE.

Application filed May 25, 1920. Serial No. 384,243.

To all whom it may concern:

Be it known that I, ROBERT WEBER, a citizen of the German Empire, residing at Dresden, Saxony, Germany, have invented 5 certain new and useful Improvements in Shutting or Fastening Contrivances (for which I have filed application in Germany on Oct. 4th, 1917, Patent No. 307803, and Germany, February 11, 1919, Patent No. 10 315690; Belgium, Jan. 1st, 1920, Patent No. 284304; Denmark, May 24th, 1921, Patent No. 27730; England, February 12th, 1920, Patent No. 159406; France, January 27, 1920, Patent No. 509161; Italy, Dec. 31st, 1919, 15 Patent No. 47/518, 181121; Norway, Dec. 30th, 1919, 33438; Switzerland, Dec. 16, 1919, Patent No. 86532), of which the following is a specification.

The subject-matter of the present invention 20 is a closure-fastener, simultaneously acting as a buffer for use at windows, doors, ventilating flaps and the like and consists of a roller or the like being held on axis of rotation of the respective wing when the 25 window is closed hereby opposing return movement, the retraction of the fastening element for opening the window being effected by means of a lever.

In the accompanying drawings one form 30 of execution of the invention is represented by way of example.

Figure 1 represents a side view of the arrangement,

Figure 2 a front view of the same,

As may be seen from the drawings *a* is a 35 roller which is held with its trunnions *b*, *b* within two brackets *c*, projecting from the window-casement *k*. Said brackets being provided with elongated slots *d*, allowing a 40 respective movement of the trunnions *b* and thereby of the roller *a* within the brackets *c* is a lever kept within two checks *f* arranged at the cross-bar 1 of the window-sash.

The arrangement is as follows:—

Two brackets *c* project from the window-casement *k*. Said brackets are provided with elongated slots *d*, in which the roller *a* is adapted to move in up-and-downward direction by means of the trunnions *b*. The 50 slots are inclined against the opening movement of the casement so that the roller, which bears against the edge of the casement on the axis of rotation of the respective wing when the window is closed is unable 55 to yield to pressure by the casement even if the same is not bolted, it being forced by

such pressure against the side of the slot. When the window is open and shall be closed, however, the roller will be forced up the slot by the casement edge thus yielding automatically. For opening the window the roller is retracted by means of a lever *e*, which is trunnioned between brackets *f* on the casement. This lever is so situated, as to move the roller up the slots *d* when actuated.

The arrangement will act as a buffer in case the door or window should be slammed and reduce the shock.

The invention is applicable to all kinds of casement windows and doors, ventilating flaps, heating, and like devices. The closure fastener is besides especially adapted for the doors of ovens and such doors which cannot be exactly closed by bolts and keys and must be kept in closed position all the same as for doors of emergency exits. The different parts may be modified in different ways without departing from the spirit of the invention.

Having now particularly described and ascertained the nature of my said invention and in what manner the same is to be performed, I declare that what I claim is:—

1. In a closure - fastener, simultaneously acting as buffer for use at windows, doors, ventilating flaps and the like, a casement, having two brackets projecting therefrom, said brackets being provided with elongated slots, said slots being inclined against the opening movement, a roller, said roller being provided with trunnions, said trunnions being movable in said slots, said roller being normally held on the axis of rotation of the window-sash, means for guiding said roller by its trunnions in upward direction as soon as the window-sash provided with said arrangement shall be moved in order to be opened and closed whereby said roller returns automatically in its original position 100 after each movement of the same.

2. In a closure - fastener simultaneously acting as a buffer for use at windows, doors, ventilating flaps and the like, a casement having two brackets projecting therefrom, said brackets being provided with elongated slots, said roller being provided with trunnions and being guided by said trunnions in said slotted brackets and normally held on the axis of rotation of the window-sash, a 110 window cross-bar, two brackets being provided at said window cross-bar and a lever

being fulcrumed thereto, said lever being adapted to move said roller in upward direction when being turned by hand in order to open the window, said roller returning automatically in its original position when the window is opened in order to prevent slamming of the window.

3. In a closure-fastener, simultaneously acting as a buffer for use at windows, doors, 10 ventilating flaps and the like, a casement having two brackets projecting therefrom and being slotted, a roller, trunnions at said roller, said roller being adapted to move up and down in said slots of said brackets, and 15 being normally held on the axis of rotation of the window-sash, a window cross-bar being provided with two brackets, a lever being fulcrumed thereto, said lever being adapt-

ed to move said roller in upward direction in order to allow the opening of the window, 20 said roller returning automatically in its original position when the window is opened thereby securing the window-sash against unwilling slamming in reducing the shock, 25 said window sash being adapted to move the roller upward when being closed and said roller being adapted to return in its original position after the window-sash is closed, so securing the window-sash against unwilling opening.

In testimony whereof I affix my signature in presence of two witnesses.

ROBERT WEBER.
